CREDENZA

Melbourne F. Smith, Lenoir, N.C., assignor to Broyhill Furniture Factories, Lenoir, N.C., a partnership

Filed Apr. 20, 1962, Ser. No. 69,792

Term of patent 14 years

(Cl. D33—13)

The end not shown is like the end shown while the back of the credenza is conventionally plain.

I claim:

The ornamental design for a credenza, as shown and described.
